ABSTRACT OF THE DISCLOSURE

Production of 3-methylbut-2-en-1-ol and 3-methylbut-2-en-1-yl acetate by isomerizing 3-methyl-3-buten-1-ol or 3-methyl-3-buten-1-yl acetate with a catalytic amount of a carbonyl compound of a metal of subgroups 6 to 8 of the Periodic System.

The present invention relates to a new process for the production of 3-methylbut-2-en-1-ol or 3-methylbut-2-en-1-yl acetate.

It is known that these compounds (also known as prenol and prenyl acetate) can be prepared in a multi-stage synthesis. This method is troublesome however and gives only unsatisfactory yields.

We have now found that 3-methylbut-2-en-1-ol or 3-methylbut-2-en-1-yl acetate can be obtained in a simple way and in high yields by treating 3-methylbut-3-en-1-ol or 3-methylbut-3-en-1-yl acetate with a catalytic amount of a carbonyl compound of a metal of subgroups 6 to 8 of the Periodic System.

The starting compounds are known and obtainable particularly advantageously by reaction of isobutene with formaldehyde followed if necessary by acetylation.

Suitable compounds which act as isomerization catalysts are particularly those of zerovalent metals in accordance with the definition, more particularly, complexes having one or two central atoms such as chromium hexacarbonyl, iron pentacarbonyl, diiron nonacarbonyl, and nickel tetracarbonyl. Compounds in which some of the carbonyl groups have been replaced by other ligands, as in dihydrogen iron tetracarbonyl or hydrogen cobalt tetracarbonyl, are also suitable.

Other suitable ligands in such compounds are those which bear basic nitrogen or phosphorus atoms. Examples of such carbonyl compounds are bis(triphenylphosphine) iron tricarbonyl and tripyridine diiron tetracarbonyl.

Iron pentacarbonyl is particularly preferred as the catalyst.

The amount of carbonyl compound required for the isomerization is from 0.01 to 20% by weight, preferably from 1 to 5% by weight, with reference to the amount of starting material to be isomerized. It is possible however to use larger or smaller amounts of these catalysts, the isomerization merely being accelerated or retarded thereby.

The reaction may be carried out at temperatures of from about 100° to 300° C., preferably from 150° to 200° C. at atmospheric pressure or at superatmospheric pressure up to about 50 atmospheres with or without a solvent and batchwise or continuously.

We have further found that particularly good results are obtained in the process by carrying out the reaction in the presence of catalytic amounts of a base or a compound having a basic reaction.

Suitable basic compounds include, in addition to inorganic bases such as sodium hydroxide, barium hydroxide or ammonia and in addition to the salts of strong bases and weak acids such as sodium carbonate or ammonium carbonate, particularly nitrogenous basic compounds such as alkylamines or arylamines and also compounds which are capable of splitting off bases, such as piperidine acetate or acid amides such as acetamide or urea. Basic compounds of phosphorus, such as alkyl and aryl phosphines, for example triphenyl phosphine, are also suitable.

Hexamethylenetetramine (urotropine) is preferred as the basic compound.

The presence of basic compounds causes a more rapid and more specific isomerization in the desired direction, i.e. from the 3-ene compound to the isomeric 2-ene compound. Since there is one more possibility of isomerization with the free alcohol than with the acetate (namely to isovaleraldehyde), the addition of base is particularly advantageous in the rearrangement of 3-methylbut-3-en-1-ol to 3-methylbut-2-en-1-ol.

The basic compound is generally used in an amount of from 0.01 to 20%, preferably from 1 to 10%, by weight with reference to the compound to be isomerized.

Hydrocarbons which are liquid under the reaction conditions concerned, as for example hexane, heptane, ligroin, benzene, toluene or xylene, are especially suitable as solvents. Moreover, high boiling point ether such as diphenyl ether, 2,2'-dimethoxydiethyl ether and 2,2'-diethoxydiethyl ether are also suitable.

Since both the starting compounds and the products of the process are sensitive to oxygen, it is advisable to carry out the reaction while excluding oxygen, for example under nitrogen or argon. When readily decomposable carbonyl compounds are used as isomerization catalysts, it may be advantageous to use carbon monoxide.

When the isomerization is over, the reaction mixture may be worked up by conventional methods, preferably by distillation.

The products of the process are valuable intermediates for organic synthesis, particularly for the production of compounds of the carotenoid and vitamin A series and of perfumes.

The invention is illustrated by the following examples.

EXAMPLE 1

A mixture of 50 g. of 3-methylbut-3-en-1-yl acetate and 3.5 g. of iron pentacarbonyl is heated for fifteen hours at 150° C. and the desired product (3-methylbut-2-en-1-yl, B.P. 110° to 112° C. at 200 mm.) is isolated from the mixture in the usual way by fractional distillation. The yield of pure products is 86% at a conversion of 42%.

EXAMPLE 2

A mixture of 2000 g. of 3-methylbut-3-en-1-ol and 10 g. of iron pentacarbonyl is heated for four hours at 140° C. and from the mixture the desired product is isolated in the usual way by fractional distillation (3-methylbut-2-en-1-ol, B.P. 102° to 105° C. at 200 mm.; $n_D^{24}=1.4408$). The yield of pure product is 63% at a conversion of 34%.

EXAMPLE 3

A mixture of 1000 g. of 3-methylbut-3-en-1-ol, 10 g. of iron pentacarbonyl and 50 g. of urotropine is heated for ninety minutes at 200° C. and the desired product is isolated from this mixture in the usual way by fractional distillation. The yield of pure 3-methylbut-2-en-1-ol (B.P. 102° to 105° C. at 200 mm.; $n_D^{24}=1.4408$) is 75% at a conversion of 50%.

EXAMPLE 4

A mixture of 150 g. of 3-methylbut-3-en-1-ol, 22 g. of iron pentacarbonyl and 9 g. of urotropine is heated for

3

thirty minutes at 200° C. and 3-methylbut-2-en-1-ol is isolated in the usual way by fractional distillation. The yield of pure product is 89% at a conversion of 31%.

EXAMPLE 5

A mixture of 1000 g. of 3-methylbut-3-en-1-ol, 15 g. of iron pentacarbonyl and 60 ml. of liquid ammonia is heated at 175° C. in an autoclave for two hours and the 3-methylbut-2-en-1-ol is then isolated by fractional distillation. The yield of pure product is 73% at a conversion of 40%.

EXAMPLE 6

A mixture of 1500 g. of 3-methylbut-3-en-1-ol, 20 g. of iron pentacarbonyl and 65 g. of piperidine acetate is heated for two and a half hours at 210° C., after which the 3-methylbut-2-en-1-ol formed is isolated by fractional distillation. The pure product is obtained in a yield of 70% at a conversion of 60%.

We claim:

1. An isomerizing process for the production of 3-methylbut-2-en-1-ol or 3-methylbut-2-en-1-yl acetate which comprises treating 3-methylbut-3-en-1-ol or 3-methyl-3-en-

4

1-yl acetate at a temperature of about 100° C. to 300° C. with a catalytic amount of iron pentacarbonyl and in the presence of a catalytic amount of a basic reacting compound selected from the class consisting of sodium hydroxide, barium hydroxide, ammonia, sodium carbonate, ammonium carbonate, piperidine acetate, acetamide, urea, alkyl and aryl amines and phosphines.

5 2. A process as claimed in claim 1 wherein said basic reacting compound is hexamethylenetetramine.

UNITED STATES PATENT OFFICE
CERTIFICATE OF CORRECTION

Patent No. 3,655,735 Dated April 11, 1972

Inventor(s) Horst Pommer et al

It is certified that error appears in the above-identified patent
and that said Letters Patent are hereby corrected as shown below:

Column 1, lines 10 to 11, "Claims priority, application Germany,
Mar. 22, 1968, P 77 68 023.8" should read -- Claims priority,
applications Germany, Dec. 8, 1967, P 16 43 709.5; Mar. 22, 1968,
P 17 68 023.8 --.

Column 3, line 22, claim 1, "3-methyl-3-en-" should read
-- 3-methylbut-3-en- --.

Signed and sealed this 21st day of November 1972.
